[57] **CLAIM**

The ornamental design for a lamp reflector, as shown
and described.

DESCRIPTION

FIG. 1 is a side perspective view of a lamp reflector
showing my new design;

FIG. 2 is a front elevational view thereof on an enlarged
scale;

FIG. 3 is a side elevational view thereof on an enlarged
scale, the opposite side being a mirror image;

FIG. 4 is a rear elevational view thereof on an enlarged
scale;

FIG. 5 is a top plan view thereof on an enlarged scale;

FIG. 6 is a bottom plan view thereof on an enlarged
scale; and

FIG. 7 is a bottom perspective view thereof.

The support arm is shown in broken lines for illustrative
purposes only and forms no part of the claimed design.
